S. L. Hockert

United States Patent Office.

S. L. HOCKERT, OF CHICAGO, ILLINOIS, ASSIGNOR TO HIMSELF AND JARED THOMPSON, SR., OF MILWAUKEE, WISCONSIN.

Letters Patent No. 70,843, dated November 12, 1867.

IMPROVEMENT IN MENSTRUAL RECEIVER.

The Schedule referred to in these Letters Patent and making part of the same.

TO WHOM IT MAY CONCERN:

Be it known that I, S. L. HOCKERT, of the city of Chicago, county of Cook, and State of Illinois, have invented a new and useful Improvement in Menstrual Receivers; and I hereby declare that the following is a full, clear, and exact description of my invention, reference being had to the accompanying drawings, forming a part of this specification, and to the letters of reference marked thereon.

The nature of my invention consists in the use of a sack, made of rubber or any other suitable materials, at the orifice of which is attached a ring made of rubber or any other suitable substance, which sack and ring are inserted in the vagina, and supported thereby by a wire, the *os uteri* resting in the ring. The wire which supports the ring is attached thereto firmly, and passes down the vagina to its external orifice, thence in a curved line to a pad, which rests on the lower part of the abdomen, and this pad is secured to the wearer by a belt, which passes around the person just above the hips.

To enable those skilled in the art to understand, make, and operate my improvement, I will proceed to describe its construction by reference to the accompanying drawings, in which—

Figure 1 represents a perspective view of my whole invention.

Figure 2 represents a side view of the sack, ring, and wire.

Figure 3 represents a full view of the ring and its external orifice.

All of the drawings are lettered, and similar letters denote corresponding parts in the several views.

I construct my menstrual receiver by forming a cup-shaped ring, *a*, made of rubber, gum, gold, silver, or any suitable substance, which may be made round, or elliptical, or of any shape to fit the *os uteri*. Around the lower orifice of ring *a* is attached a sack or bag, *b*, made of rubber or any suitable materials. The ring *a* rests around the *os uteri*, and the bag *b* rests entirely in the vagina, or may be made of such length as to rest partly outside and partly inside. I insert a small sponge in bag *b* to absorb the menstrual flux. To the ring *a* is attached a wire or arm, *c*, made of silver, or of any other suitable substance, and supports ring *a* and sack *b* in position. Arm *c* passes directly downward from the place of its attachment to ring *a*, along the side of sack *b*, and on reaching the orifice of the vagina curves gradually upwards, as shown in fig. 2, and passes perpendicularly through projection *h*, and is there held fast by set-screw *d*, the arm being free to move in a vertical direction when the set-screw is loose. Projection *h* is firmly attached to pad *e*; as shown by fig. 1. Pad *e* is made of silver, rubber, or any suitable substance, and may be of any shape to fit the form of the wearer. This pad is attached to belt *f f* by thread, or in any other convenient manner, and is supported by said belt *f f* in its place. The belt *f f* is fastened around the waist of the wearer by buckle *g*. *I* is a cord attached in any convenient manner to the bottom of sack *b*, and used for the purpose of enabling the wearer to remove the sack from the vagina with ease.

Having stated the construction and operation of my invention, what I claim, is—

The construction and combination of ring *a*, sack *b*, and arm *c*, for the purposes and in the manner substantially as hereinbefore shown.

I also claim the combination of ring *a*, sack *b*, arm *c*, and cord *i*, for the purposes and in the manner as hereinbefore set forth, or their equivalent.

I also claim a combination of ring *a*, sack *b*, arm *c*, cord *i*, pad *e*, projection *a*, set-screw *d*, belt *f f*, and buckle *g*, for the purpose and in the manner hereinbefore set forth.

S. L. HOCKERT.
